UNITED STATES PATENT OFFICE.

ADOLPH A. WALRODEN, OF NORWICH, CONNECTICUT.

DOUBLE-MOTION CAM DEVICE.

Application filed August 30, 1921. Serial No. 496,936.

To all whom it may concern:

Be it known that I, ADOLPH A. WALRODEN, a citizen of the United States, residing at 5 Norwich, in the county of New London and State of Connecticut, have invented certain new and useful Improvements in Double-Motion Cam Devices, of which the following is a specification, reference being had therein to the accompanying drawings.

10 This invention relates to a double motion cam device, and has for its object the construction of a simple and efficient device which will enable an operator to adjust the jaws slowly or quickly by the rotation of a 15 cam plate through the medium of a handle, gripped by the operator.

Another object of the invention is the construction of a double motion cam vise of a simple and efficient construction, adapted 20 for controlling presses, milling machines, and bench assembling but can be used successfully in horizontal and vertical tapping machines, as well as turret lathes.

With these and other objects in view, my 25 invention comprises certain novel combinations, constructions and arrangements of parts as will be hereinafter described, illustrated in the accompanying drawings, and more particularly pointed out in the appended claims.

In the drawings:

Figure 1 is a vertical sectional view through the device, while

Figure 2 is a top plan view of the same, 35 showing a part of the cap plate broken away.

Figure 3 is a sectional view taken on line 3—3, Fig. 1, with the drum and pin removed.

Figure 4 is a plan view of the cam plate.

Referring to the drawings by numerals, 1 40 designates the bed plate having a central opening 2, and the bed plate is provided with bifurcations 3 at opposite sides, for receiving any suitable means for fastening the bed plate to a carriage or support.

45 Resting upon the bed plate 1 is a cap plate 4. This cap plate is provided with an inner annular flange 5 and an outer annular flange 6. The annular flange 5 extends down into the opening 2, and the annular flange 6 rests 50 against the outer edge of the bed plate 1, Figs. 1 and 2. The cap plate is fastened securely to the bed plate, against rotary movement.

The cap plate is provided with aligned 55 elongated slots 7, and with raised ledges 8 between which is formed a groove 9. Posi-

tioned upon the ledges 8 are detachable plates 10, the inner edges of which plates 10 overhang the groove 9 and securely fastens the two sliding jaws 11 upon the cap plate; 60 the bolts 12 fasten the plates 10 upon the ledges 8.

Each jaw 11 comprises an elongated body having an upwardly-extending apertured lug 13, and depending from the bottom of the 65 body is an integral primary extension 14, terminating in a reduced extension 15. The primary depending extensions 14 of the jaws 11 are positioned in the elongated slots 7 of the cap plate 4, under the groove 9. 70

A cam plate 16 rests upon the top of the bed plate 1, under the cap plate 4. This cam plate 16 is provided with a large, central aperture 17, which allows the cam plate 16 to be rotatably mounted around the flange 75 or hub 5 of the cap plate 4, Figs. 1 and 3. Extending through a suitable slot, formed between the dotted lines 18, Fig. 2, upon the side of the cap plate 4 is a handle 19, which handle is securely fastened, at 20, Fig. 1, to 80 the cam plate 16. Upon moving the handle 19, the cam plate 16 will be rotated around the flange 5 for moving the jaws 11 upon the cap plate.

The cam plate is provided with a pair of 85 similarly constructed grooves; each groove is provided with a primary long portion 21 and an auxiliary short portion 22. In the grooves are rollers 23 (Figs. 2 and 3), and the auxiliary extensions 15 extend into the 90 rollers 23, so that upon rotating the cam plate 16, through the medium of the rollers 23 and extensions 15, of the jaws 11, said jaws will be adjusted. In adjusting the jaws 11, when the cam plate 16 is being 95 rotated for causing the primary long portions 21 to pass under the slots 7 (Fig. 2), a very slow action or movement of the jaws 11 will be caused, but when the short auxiliary portions 22 are traveling directly under 100 the slots 7, the adjustment of the jaws outwardly upon the cap plate will be more rapid; the action of the primary portions 21, acting upon the jaws will be to draw them toward each other very slowly; hence, it 105 will be seen that I have provided a cam plate with two slots, each having portions at an angle to each other, the portion 21 being for slow adjustment and the portion 22 being for fast or rapid adjustment of a jaw. 110

The drum 24 is placed in the opening 2, and a threaded pin 25 is mounted in the

drum, and by means of lock nuts 26, the pin is retained in an adjusted position upon the drum 24. The upper end of the pin 25 is socketed, as shown by dotted lines 27; this pin 25 extends through the aperture 28 (Fig. 3) of the cap plate and is used for some work which requires a stop on the bottom.

5 A bracket arm 29 may be fastened to the 10 cap plate by means of a bolt 30; this bracket arm 29 is used for some work that is required for close work where a tool is supposed to pass through the bushing 29^a.

15 In such work as does not require the drum 24, pin 25, and lock nuts 26, the same may be removed to permit the work to drop through the vise in the box, thus increasing the production of the operator.

20 It is to be understood that the bed plate 1 and the cap plate 4 fit closely together to protect the cam plate 16 from being damaged in operation, and the close-fitting of said parts prevent chips or dust from entering therebetween, insuring, by keeping the parts 25 clean, of very efficient operation.

In the jaws 13' are horizontal slots 13^a made for insertion of different jaws to suit different work.

30 The reason of the slow motion of the jaws, caused by depending projections of said jaws extending into the portions 21 of the cam plate, is to lock the work, giving a strong grip to the work, and preventing it from getting loose in operation.

35 While I have described the preferred embodiment of my invention, and have illustrated the same in the accompanying drawings, certain minor changes or alterations may appear to one skilled in the art to which 40 this invention relates, during the extensive manufacture of the same and I, therefore, reserve the right to make such alterations or changes as shall fairly fall within the scope of the appended claims.

45 What I claim is:

1. In a device of the class described, the combination of a bed plate, a cap plate provided with an inner and outer annular flange resting upon the bed plate, the inner flange

engaging the inner portion of the bed plate 50 and the outer flange engaging the outer face of the bed plate, said cap plate provided with a pair of ledges and a groove formed between said ledges, jaws slidably mounted in said groove, and cam means positioned 55 between the bed plate and the cap plate and operably connected to the jaws for adjusting the jaws in the groove when said cam means is operated.

2. In a device of the class described, the 60 combination with a bed plate, of a cap plate resting upon and secured to said bed plate, said cap plate provided with inner and outer flanges engaging the inner and outer portions of the bed plate, said cap plate provided with a groove in its top and with an opening in its side, a rotatable cam plate under said cap plate and resting upon the bed plate, a handle fastened to the cam plate and extending through the opening in the 70 side of the cap plate, slideable jaws positioned upon said cap plate, and means secured to the jaws and extending through the cap plate and into the cam plate for adjusting the jaws when the cam plate is moved by an 75 operator grasping and operating the handle.

3. In a device of the class described, the combination with a bed plate, of a cap plate on said bed plate, said cap plate provided with elongated slots, jaws positioned on said 80 cap plate above said slots, a cam plate under said cap plate, said cam plate provided with a pair of slots, each slot comprising a primary long portion and an auxiliary short portion positioned at angles to each other, 85 said slots of the cam plate registering with the slots in the cap plate, rollers in the slots of the cam plate, and said jaws provided with integral depending primary portions and with reduced auxiliary portions, the 90 primary portions positioned in the slots of the cap plate and the auxiliary portions positioned in the rollers, substantially as shown and described.

In testimony whereof I hereunto affix my 95 signature.

ADOLPH A. WALRODEN.
